UNITED STATES PATENT OFFICE.

LEWIS A. HAMILTON, OF ELKO, NEVADA.

RAILROAD-TIE.

1,107,063.

Specification of Letters Patent. Patented Aug. 11, 1914.

Application filed December 6, 1913. Serial No. 805,080.

To all whom it may concern:

Be it known that I, LEWIS A. HAMILTON, a citizen of the United States, residing at Elko, in the county of Elko and State of Nevada, have invented new and useful Improvements in Railroad-Ties, of which the following is a specification.

The present invention relates to improvements in ties for railway rails.

10 In carrying out my invention I propose to construct a tie of a metallic jacket or casing susceptible to a certain amount of yieldability, and being provided with a filler of compressed saw-dust which has been 15 treated with a preservative preferably of creosote and tar, which will not interfere with the resiliency of the tie, and whereby the rails will be afforded the desirable amount of elasticity.

20 A further object of the invention is the provision of means which may be removably connected with the tie for retaining the rails upon the tie.

25 With the above and other objects in view, the improvement resides in the construction, combination and arrangement of parts set forth in the following specification and falling within the scope of the appended claims.

30 In the drawings: Figure 1 is a perspective view of my improvement showing the same supporting rails. Fig. 2 is a central longitudinal sectional view through the same, Fig. 3 is a transverse sectional view, and Fig. 4 is a perspective view of the rail retaining member. Fig. 5 is a detail longitudinal sectional view taken through one 35 end of the tie illustrating the manner whereby the end plate may be secured to within the shell of the tie.

40 Referring now to the drawing in detail, 1 designates a shell or casing constructed preferably of soft steel alloyed with copper. The shell or casing is of the required size and shape, and may include closed ends if 45 desired, and the alloy of steel and copper renders the shell sufficiently resilient as to not interfere with the yielding of the rails thereon when rolling stock passes over the rails, which renders the tie equal in efficiency 50 to the ordinary wooden ties, and of a decidedly cheaper construction.

The shell has compressed therein a filler of saw-dust 2, the said saw-dust during the process of compressing the same within the shell being treated with a preservative, preferably of creosote and tar. The preservative

is adapted to hold the articles of the saw-dust against separation, but at the same time the treatment does not interfere with the yieldability of the compressed filler, and furthermore, the saw-dust thus treated will not be affected by moisture or by climatic changes.

The upper face of the shell 1 may be integrally formed with longitudinally extending enlargements or plates 3 which are disposed adjacent to the opposite ends of the ties, and each of the plates is integrally formed with an angularly arranged inturned lip 4, and each of said lips conforms in shape to the base flanges upon the outer faces of the rails, with which the said lips are adapted to engage. In the showing of the drawing, the plates 3 are illustrated as connected with the shell through the medium of rivets 5, and in order to sustain the rails tightly against the lips 4, the plates are provided with one or more openings 6 spaced a suitable distance from the lips and adapted to receive headed bolt members 7, which may pass through the upper and lower faces of the shell as well as the filler of the shell and be retained upon the tie through the medium of retaining nuts 8, as shown upon the left hand side of Fig. 2, or the bolt may pass through the openings 6 in the plate 3 and have their shanks embedded within the filler 2 as shown on the left hand side of said Fig. 2. The heads of the bolts are adapted to overlie the inner longitudinal edges of the rails R, and by this means the said rails are effectively sustained upon the tie.

While in Figs. 1 and 2 of the drawings, the end plates are illustrated as secured to the ends of the shell 1 through the medium of rivets, I have found it preferable to bend or crimp one of the ends, as illustrated in Fig. 5, to provide inturned flanges A, and then insert one of the end plates B through the opposite end of the shell and rests upon the flanges A. When one of the plates B is thus positioned the shell and a filler 2 inserted and tamped within the shell, after which a second plate is inserted over the filler within the second end of the tie, and the edges of the said ends are bent over the second plate B, thus closing the ends and retaining the filler within the shell.

From the above description, taken in connection with the accompanying drawing, the simplicity of the device as well as the advantages thereof will, it is thought, be per-

fefully apparent to those skilled in the art to which such invention appertains without further detailed description.

Having thus described the invention, what I claim is:

- 5 1. A tie comprising a shell formed from soft steel alloyed with copper and having a filler of compressed saw-dust.
- 10 2. A tie including a shell of soft resilient metal, a filler for the shell, said filler comprising saw-dust treated with a preservative of creosote and tar and compressed within the shell, and means provided by the tie for

retaining the rails upon the tie, said means comprising plates having integrally formed angular lips which engage the outer base flanges of the rails, and bolts passing through the plates to within the tie and having their heads engaging with the inner base flanges of the rail.

20 In testimony whereof I affix my signature in presence of two witnesses.

LEWIS A. HAMILTON.
